[57] CLAIM

The ornamental design for a tubular food container, as shown and described.

DESCRIPTION

FIG. 1 is a typical elevational view of a tubular food container showing my new design;

FIG. 2 is a bottom plan view thereof;

FIG. 3 is a top plan view thereof;

FIG. 4 is a perspective view of an inner support bar of FIG. 1; shown separately for clarity; the broken line showing of food chips is for illustrative purpose only and forms no part of the claimed design;

FIG. 5 is a side elevational view of FIG. 4;

FIG. 6 is a bottom plan view of FIG. 4; and,

FIG. 7 is a top plan view of FIG. 4.
